CLAIM

The ornamental design for a programmable controller, as shown and described.

DESCRIPTION

FIG. 1. is a perspective view of the front, top, and left sides of a programmable controller showing a first embodiment of our new design;

FIG. 2. is a front view thereof;

FIG. 3. is a rear view thereof;

FIG. 4. is a top plan view thereof;

FIG. 5. is a bottom view thereof;

FIG. 6. is a right side view thereof;

FIG. 7. is a left side view thereof;

FIG. 8. is a perspective view of the front, top, and left sides of a programmable controller showing a second embodiment of our new design;

FIG. 9. is a front view thereof;

FIG. 10. is a rear view thereof;

FIG. 11. is a top plan view thereof;

FIG. 12. is a bottom view thereof;

FIG. 13. is a right side view thereof;

FIG. 14. is a left side view thereof;

FIG. 15. is a perspective view of the front, top, and left sides of a programmable controller showing a third embodiment of our new design;

FIG. 16. is a front view thereof;

FIG. 17. is a rear view thereof;

FIG. 18. is a top plan view thereof;

FIG. 19. is a bottom view thereof;

FIG. 20. is a right side view thereof; and,

FIG. 21. is a left side view thereof.

The broken lines shown represent portions of the programmable controller and form no part of the claimed design.

1 Claim, 21 Drawing Sheets
